UNITED STATES PATENT OFFICE.

JAMES A. ROUNDS, OF ATLANTIC CITY, NEW JERSEY.

SHADE-FIXTURE.

1,130,729.

Specification of Letters Patent.

Patented May 18, 1915.

Application filed October 10, 1913. Serial No. 794,444.

To all whom it may concern:

Be it known that I, JAMES A. ROUNDS, a citizen of the United States, residing at Atlantic City, in the county of Atlantic and State of New Jersey, have invented certain new and useful Improvements in Shade-Fixtures; and I do hereby declare the following to be a full, clear, and exact description of the invention, such as will enable others skilled in the art to which it appertains to make and use the same.

This invention relates to shade fixtures, and the principal object thereof is to provide brackets for holding shade rollers, said brackets adapted to be secured to the sashes or casing of a window.

Another object of the invention is to provide window shade brackets which will be simple, durable, inexpensive to manufacture, efficient in operation, and which may be quickly and easily secured in place or removed without the requirement of skilled labor or of any but ordinary tools.

With these and other objects in view the invention resides in the construction, combination, and arrangement of parts herein-after more fully described and claimed and illustrated in the accompanying drawing in which like characters of reference indicate like parts throughout the several figures of which—

Figure 1, represents a front elevational view of a window showing the application of the invention. Fig. 2, represents a perspective view of a bracket for receiving a squared shade roller pin. Fig. 3, represents a perspective view of a bracket for receiving a round shade roller pin, Fig. 4, represents a vertical, transverse, sectional, view of a portion of the top rail of a window sash showing the invention applied thereto and Fig. 5, represents a plan view of the blank from which the brackets are formed.

Referring more particularly to the drawing, the numeral 5 indicates a window casting, and the numerals 6 and 7 indicate the upper and lower sashes respectively, and in Fig. 1, I have shown the shade brackets as attached to the top rails of the window sashes, and also to the top of the casing.

The brackets comprise a body 8 having a top 9 at right angles to the body and down turned teeth 10 at right angles to top 9 and parallel to the body 8, and an ear 11 is formed at right angles to body 8, the ears of certain of the brackets having a recess 12

cut therein for receiving the squared pins 13 of shade rollers 14 and others of the brackets having their ear provided with round openings 15 for round pins of said rollers.

In Fig. 5, there is represented the form of blank from which the brackets are made, said blank being substantially rectangular and provided in one side with a transversely extending slit 16 which forms the upper edge of the ears 13, when the same are bent along the longitudinal line 17, it being noted that the ears are long enough to sufficiently space the shade rollers from the window sashes so as to allow the window shades to be entirely rolled up without coming in contact with the sashes of the window as the diameter of the roll increases. The top portion 9 is adapted to be bent along the transversely extending line 18 and the prongs 10 which are formed to one edge of the blank are adapted to be bent along the transversely extending line 19. The portion 20 of the brackets occurring between the ears and the top portion 9 has its corner rounded as at 21 and the lower corner 22 of the body of the brackets is rounded as are also the lower and outer edges of the ears so that no sharp corners are left which might catch in curtains and by thus rounding the various portions, a more graceful and attractive bracket is formed.

In securing a bracket in place, the body portion 8 is held against the outer face of the top rail of a window sash with the body portion 9 projecting over the rail, and with the teeth or prongs 10 resting against the upper edge of the rail, and the top 9 may then be forced downwardly so that the teeth are buried in the wood of the rail as illustrated in Fig. 4 thus securely holding the bracket in place. As the line 17 on which the ear 13 is bent is substantially the vertical or longitudinal center of the bracket, it is obvious that the strain exerted thereon by the shade roller 14 is evenly distributed over the entire bracket. The portions 20 and 22 of the body lie against the window shade or frame on opposite sides of the vertical plane of the ear 13 and thus secure the bracket against swinging movement. Brackets constructed according to my invention will not mar or disfigure a visible portion of the window to which they are applied as is a common fault with most brackets and window shade attachments. They are very in-

conspicuous and afford a very attractive appearance and at the same time are very easily attached or detached, and do not require the use of screws or bolts or other securing means ordinarily used.

Although I have described the preferred embodiment of my invention, I may desire to make such changes as do not depart from the spirit of the invention and the scope of 10 the appended claims.

Having thus fully described my invention, what I claim as new and desire to secure by Letters Patent is:—

A curtain bracket formed of a blank having parallel side edges with an approximately centrally disposed transverse slit, and a projecting ear portion adjacent said

slit with rounded corners, said ear being provided with means for engaging and supporting a curtain roller, and being bent at 20 right angles to the main body portion along the medial line of said body portion, the front edge of said body being serrated and bent to bring said teeth or serrations into spaced parallel relation with said body, said bracket thus being formed from a blank of substantially rectangular outline.

In testimony whereof I have signed my name to this specification in the presence of two subscribing witnesses.

JAMES A. ROUNDS.
